UNITED STATES PATENT OFFICE.

LLOYD M. MILLS, OF GRAND RAPIDS, MICHIGAN.

CASH RECORDER AND DRAWER.

SPECIFICATION forming part of Letters Patent No. 487,284, dated December 6, 1892.

Application filed September 5, 1891. Serial No. 404,836. (No model.)

To all whom it may concern:

Be it known that I, LLOYD M. MILLS, of Grand Rapids, in the county of Kent and State of Michigan, have invented a new and Improved Cash-Recorder, of which the following is a full, clear, and exact description.

The invention relates to cash recorders and indicators such as shown and described in the Letters Patent of the United States, No. 434,799, granted to me on the 19th day of August, 1890.

The object of the present invention is to provide a new and improved cash-recorder which is simple and durable in construction and arranged to print on a tape a record of all sales made and also to print on a tape a detachable ticket indicating the individual sale.

The invention consists of certain parts and details and combinations of the same, as will be hereinafter described, and then pointed out in the claims.

Reference is to be had to the accompanying drawings, forming a part of this specification, in which similar letters of reference indicate corresponding parts in all the figures.

Figure 1 is a sectional side elevation of the improvement on the line 1 1 in Fig. 2. Fig. 2 is a sectional plan view of the same on the line 2 2 in Fig. 1. Fig. 3 is a vertical sectional front view of the same. Fig. 4 is a sectional side elevation of part of the improvement on the line 4 4 in Fig. 3. Fig. 5 is an enlarged face view of the inclined plate for one of the type-bars. Fig. 6 is a plan view, with parts in section, of the tape or paper carriage. Fig. 7 is a sectional side elevation of a modified form of the improvement; and Fig. 8 is a front view of the cutting mechanism, with parts in section.

The improved cash-recorder is provided with a suitably-constructed casing A, in the bottom of which is mounted to slide a money-drawer B, adapted to be locked in a closed position by a locking-bolt B', arranged vertically and adapted to engage with its lower end a notch B², formed in the top of the drawer B near its rear end. The locking-bolt B' is pivotally connected with a lever C, fulcrumed within the casing A and extending with its front end through a slot A' in the front of the casing A. The outer end of this

lever C carries a finger-piece D, marked "1-9 C," meaning one to nine cents. (See Fig. 2.) When the lever C is pressed, the bolt B' is lifted out of the notch B² and the money-drawer B is free to open, the opening movement being accomplished by a spring B³, as plainly shown in Fig. 1, or by other mechanism, as illustrated in Fig. 7 and hereinafter more fully described. The spring B³ is arranged in the bottom of the casing A and is connected at one end to the said casing and at its other end to the drawer B, the line of tension being longitudinal—that is, in line 65 with the movement of the drawer.

Near but in front of the center of the lever C is arranged a pivot E, on which is fulcrumed a series of levers C', C², and C³, (see Fig. 2,) all extending forward through the front end of the casing and passing through vertical slots A², A³, and A⁴, respectively, formed in the front end of the casing and of different heights to limit the swinging motion of the respective levers. On the outer ends of the said levers C', C², and C³ are finger-pieces D', D², and D³, respectively, of which the finger-piece D' is marked "10-99 cents," the finger-piece D² is marked "\$1-\$9.," and the finger-piece D³ is marked "\$10.-\$99.," which indicates that when the respective finger-pieces are pressed the paper is shifted to print the sums in the proper place on the paper, as hereinafter more fully described.

On top of the lever C', within the casing A, is arranged a cross-piece C⁴, extending over the top of the lever C. A similar cross-piece C⁵ is attached to the lever C² and extends over the tops of both levers C' and C. Another cross-piece C⁶ is secured to the lever C³ and extends over all the other levers C², C', and C, as plainly indicated in Figs. 1 and 2. A spring C⁷, drawing on the lever C, holds the latter in an uppermost position, and as the said lever abuts against the under side of the cross-pieces C⁴, C⁵, and C⁶ the several levers C', C², and C³ are held in a like uppermost position by the said lever and spring. When the operator presses the finger-piece D, the lever C swings downward at its front end, the rear end rising to lift the bolt B', as above described, the other levers C', C², and C³ remaining undisturbed. When the operator presses on the finger-piece D', the lever C'

swings down until it reaches the bottom of the slot A², the cross-piece C⁴ of the said lever carrying the lever C downward with the lever C'. Thus when the finger-piece D' is pressed 5 the lever C is also actuated to withdraw the bolt B' from the notch B².

When the finger-piece D² is pressed, the lever C² swings downward and by its cross-piece C⁵ causes a downward swinging motion of 10 the levers C' and C, the downward motion, however, being limited by the lever C² striking the bottom of its slot A³, which is of a less height than the other two slots A' and A² for the levers C and C'. In a like manner when 15 the finger-piece D³ is pressed all the other levers are set in motion, the lever C receiving sufficient movement to lift the bolt B' out of the notch B² to unlock the drawer B.

Near the front end of the lever C is pivoted 20 an arm F, which extends downward and is pivotally connected with a lever F', (see Figs. 1 and 3,) fulcrumed on a bracket extending from a frame G, secured within the casing A. The frame G supports the type-bars H and 25 the paper or tape carriage I. The latter is provided with a laterally-extending arm I', engaged by the inclined under side of the lever F'; so that when the lever C is pressed the arm F imparts a swinging motion to the 30 lever F', and the latter, pressing on the arm I', causes a transverse shifting of the paper or tape carriage, as will be readily understood by reference to Fig. 3 and as hereinafter more fully described.

35 The type-bars H are composed of a series of rods H', preferably arranged in two rows and diverging from a common point, so that when pressed the types on the lower ends of the said rods press upon the same spot. The 40 type-rods extend through the top of the casing A, and each is provided with a finger-piece H², marked with a numeral. Curved springs H³ are secured in the casing A and are connected with the type-rods H, so as to 45 hold the same in an uppermost position, as is plainly shown in Figs. 1, 2, 3, and 7. Usually ten type-bars are employed, the finger-pieces H² being provided with the numerals from "0" to "9," as plainly shown in Fig. 2. The type-bars are of the same construction and act 50 similar to the ones described in the patent above referred to.

The paper or tape carriage I is provided on the left-hand side with an arm I², which 55 forms a continuation of the arm I', and is also fitted to slide transversely in the frame G. (See Figs. 2, 3, and 6.) On top of this arm I² are arranged ratchet-teeth I³ for shifting the carriage sidewise, as hereinafter more fully 60 described. The rear end of the carriage I is mounted on a rod I⁴, extending transversely and secured on suitable brackets fastened to the bottom of the casing A. From one side of the carriage I extends an arm I⁵, adapted 65 to be engaged by a wedge B⁴, supported from the drawer B on a plate B⁵, extending upward from one side of the drawer through a slot in

the bottom of the casing, as plainly illustrated in Figs. 2 and 4. When the drawer is closing, the wedge B⁴ engages the arm I⁵, thus 70 causing a transverse sliding of the paper-carriage I, so that the latter is returned to its normal position to the right of frame G.

Over and under the transverse bar I' of the carriage I passes a paper tape J, unwinding 75 from a roll J' and adapted to wind up on a roll J², both journaled within the casing A, near the rear end of the same, as plainly shown in Fig. 1. The flanges of the rolls J' and J² are held in frictional contact with each 80 other, so that when the tape J is pulled to unwind from the roll J' the other roll J² turns by frictional contact with the roll J' to wind up the paper. The tape J extends to the front of the casing A and passes first under a 85 roller J⁴ and then over a roller J⁵, journaled in the front end of the carriage I. The tape also passes under a spring-pressed roller J⁶, located intermediate of the rolls J' J² and the roller J³ and being journaled in the frame I. 90 The lower part of the tape J on its rearward passage from the rollers J⁴ passes between two rollers J⁵ and J⁶, journaled in the frame I. The roller J⁵ is pressed on by a spring J⁸, so as to firmly press the paper between the 95 two rollers to prevent shifting of the paper.

Over the upper part of the tape J, near its front end and directly above the bar I', passes the lower part of an endless ink-ribbon K, extending transversely and passing around rollers K' and K², journaled in the sides of the frame G. (See Figs. 3, 6, and 7.) Beneath the ink-ribbon K passes a second paper tape L, which unwinds from a roller L', journaled within the casing A, and passes under a 105 roller L² beneath the ink-ribbon and then forward and outward through a slot A⁶ in the hinged front A⁷ of the casing A. (See Figs. 6 and 7.) The roller L² is located directly above the roller J⁴, so that the tape L in passing under the roller L² is pressed on by the roller J⁴, which latter is forced upward by a suitable spring W (shown in dotted lines in Fig. 7) to 110 give sufficient tension to the paper.

The ink-ribbon K is arranged in line with 115 the printing-point of the type-bars, so that when one of the latter is pressed an impression is made simultaneously on both tapes L and J over the bar I', which latter, between the sides of the frame G, serves as an impression-block.

The necessary motion for the tapes J and L is derived from the drawer B when closing the latter. For this purpose the shaft J⁷ of the roller J⁶ is provided with a ratchet-wheel 120 N, adapted to be engaged by a pawl N', pivoted on a rod N², mounted to slide longitudinally in suitable bearings secured on the carriage I. The rear end of the rod N² is formed with a downward projection N³, adapted to be 125 engaged by the back of the drawer B, so that in closing the drawer the rod N² is pushed rearwardly, whereby the pawl N' pulls on the ratchet-wheel N, thus giving a rotary motion 130

to the latter and to the roller J^6 . The tape J , passing between the roller J^6 and the spring-pressed roller J^5 , is caused to travel when the roller J^6 revolves, as previously described, so that the tape is unwound from the roll J' and wound upon the roll J^2 and passes over the impression-block I' . In order to insure a return movement of the rod N^2 , a spring N^4 is coiled on the said rod and rests with one end against one of the bearings for the rod and with its other end on a collar N^5 , secured on the rod N^2 . When the rod N^2 slides rearwardly on closing the drawer B , the spring N^4 is compressed, and when the drawer is opened the said spring exerts a forward pull on the rod N^2 , so that the pawl N' moves forward to engage the teeth on the ratchet-wheel N . The forward movement of the rod N^2 is limited by a slotted arm I^6 , projecting from the frame I , and through which passes the bent arm N^3 of the said rod, as plainly understood by reference to Figs. 1, 2, and 7. The tape L is also actuated by the rod N^2 . For this purpose the shaft L^3 of the roller L^2 is provided with a ratchet-wheel L^4 , engaged by a projection or pawl N^6 , held on the rod N^2 . When the latter moves rearward, the projection or pawl N^6 pulls on the ratchet-wheel L^4 , so that the roller L^2 is turned and the tape L is moved forward. A gravity-pawl L^5 prevents a return movement of the roller L^2 .

The ratchet-teeth I^3 on the bar I^2 of the paper-carriage I are adapted to be engaged by a pawl O , held on a lever O' , pivoted on the frame G and adapted to rest on the upper end of an arm O^2 , pivoted on the frame G and extending downward through a slot in the bottom of the casing A , the lower end of the said lever O^2 travelling in a notch or slot B^6 , formed in the top of the drawer B . A spring O^3 is connected with the upper end of the said lever O' to hold the latter in an uppermost position. The lever O' is adapted to be engaged and pressed on by a pin H^4 , held in each of the type-rods H' , so that when one of the rods H' is pressed downward its pin H^4 engages the lever O' and presses the same downward, so that the outer end of said lever O' , carrying the pawl O , is raised. The pawl O , according to the movement of the lever O' , engages the next following ratchet-tooth I^3 to shift the paper-carriage I in the manner and for the purpose hereinafter more fully described. On the lever O' is also pivoted a pawl K^4 , engaging a ratchet-wheel K^3 , held on the shaft of the roller K^2 , over which passes the ink-ribbon K . The pawl K^4 is prevented from moving too far by a pin held on the lever O' and engaging a slot on pawl K^4 , as shown in Fig. 3. When the lever O' swings downward and when the lever O' swings upward, the pawl K^4 imparts a rotary motion to the ratchet-wheel K^3 , so that the ink-ribbon roller K^2 turns, and thus a transverse traveling motion is given to the ribbon. Thus the type-bars when pressed in succession engage the ribbon at a new point as the ribbon I is

shifted by each full stroke of each respective type-bar.

In order to lift the pawl O out of contact with the ratchet-teeth I^3 , the shaft P' is provided with an arm P , rigidly secured thereon and engaging the under side of the said pawl O . The shaft P' is mounted to turn in suitable bearings erected on the bottom of the casing A . On the shaft P' is secured, also, an arm P^2 , which extends downward through a slot in the bottom of the casing and is adapted to alternately engage two notches B^7 and B^8 , formed in one side of the drawer B . (See Fig. 4.) When the drawer is moved outward, as previously described, the lower end of the arm P^2 travels up the incline of the notch B^7 , so that the shaft P' turns in its bearings and its pin P swings upward, thus lifting the pawl O out of mesh with the ratchet-teeth I^3 . On the further opening of the drawer B the arm P^2 travels down the inclined side of the other notch B^8 , so that the shaft P' turns back to its former position, thus lowering the pin P and permitting the pawl O to drop to engage whatever tooth I^3 is below it. At the same time the arm P^2 forms a stop for the drawer B to prevent the latter from being drawn out too far. The lower end of the arm P^2 then rests against the bottom of the notch B^8 , as will be plainly understood by reference to Fig. 4, and the vertical rear wall of the notch B^8 coming against the arm P^2 prevents the drawer from being pulled out farther.

In order to enable the operator to print any one of the several desired remarks on the tapes L and J , the type-bar H^5 is provided, similar in construction to the type-rods H , but instead of carrying a single type at its lower end it carries a type-disk H^6 , (see Fig. 5,) provided with a series of characters indicating "paid," "change," "out," and other desirable matter for printing cash sales, or by what salesman the sale was made, or in which department, or the amount of cash paid out or received on account of goods returned, or charge made. The type-bar H^5 can be turned so that either of the characters is brought directly over the tapes L and J , near one edge, so that when the type-bar is pressed the corresponding character will be printed on the tapes L and J . The type-bar H^5 is provided with a finger-piece H^7 and a pin H^8 , indicating on a fixed plate H^9 , (see Figs. 1 and 2,) provided with characters corresponding to the characters of the type-plate H^6 , so that the operator can conveniently tell the proper position of the respective character on the plate H^6 relative to the tapes.

Instead of opening the drawer B by means of the spring B^3 after the locking-bolt B' is withdrawn the opening of the drawer may be accomplished by the movement of the lever C , the latter being connected for this purpose with a link R , pivotally connected with a bell-crank lever R' , pivoted within the casing A and pivotally connected by a link R^2 with a

- rigid arm R^3 , extending upward from the drawer B and adapted to travel in a longitudinal slot R^4 in the casing above the drawer. The link R is slotted at its connection with the lever C , so that when the latter is pressed the bolt B' is withdrawn before the said lever C acts on the link R . After the bolt is withdrawn and the lever C is further actuated the link R pulls on the bell-crank lever R' , which latter causes the link R^2 to press forward on the drawer B and move the arm R^3 in its slot, thus opening the same.
- The operation is as follows: When the drawer B is closed and the several parts are in the position illustrated in the drawings and, for instance, a sale of one dollar and twenty-five cents is to be marked, then the operator presses the unlocking-lever C^2 until a further downward motion is prevented by the lever, striking the bottom of the slot A^3 . By pressing the lever C^2 the locking-bolt B' is raised out of the notch B^2 in the top of the drawer B , so that the drawer is unlocked and the spring B^3 or bell-crank lever R' and link R^2 forces the drawer B open. By this movement of the lever C^2 and corresponding movement of the levers C' and C , as previously explained, the latter lever C by the arm F and lever F' , acting on the bar I' , shifts the frame one space to the left. The outward movement of the drawer B allows the lower end of the locking-lever, O^2 to drop into a perpendicular position, thus freeing the upper end of the said lever from the lever O' . The outward movement of the drawer B also allows the spring N^4 to move the rod N^2 a sufficient distance to the front of the casing to drop the pawls N' and N^6 into the next teeth on the ratchet-wheels N and L^4 , as previously explained. The operator then presses down on the finger-piece H^2 of the type-rod H' carrying the numeral "1", so that the said type-rod in its downward movement strikes with its pin H^4 on the lever O' , thus moving the latter downward a sufficient distance to allow the pawl O to drop into the next tooth in the ratchet-teeth I^3 . The further desired movement of this type-bar brings its type in contact with the ink-ribbon K , so that the numeral "1" is printed on the tape L and also, by the assistance of the lower part of the ink-ribbon, on the tape J on top of the block I' . As soon as the operator releases the pressure on the type-bar its spring H^3 returns it to its uppermost or normal position and the spring O^3 pulls the lever O' back to its normal position. The pawl O on this upward movement of the lever O' acts on its respective tooth, so that the carriage I is shifted one space to the left at the same time the ink-ribbon K is shifted by the action of the pawl K^4 and the ratchet-wheel K^3 . The type-bar bearing the numeral "2" is then depressed and the above operation is repeated—that is, the numeral "2" is printed on the two tapes L and J on the right-hand side of figure "1" and the carriage I is shifted

one space to the left by the pawl O , as above described. The operator now presses the type-bar carrying the numeral "5," so that its numeral is printed to the right of the figure "2" 70 on both tapes L and J . The operator now closes the drawer B , and the wedge B^4 , acting on the arm I^5 moves the carriage I back to its normal position to the right, as previously mentioned. Previous to the wedge B^4 engaging the arm I^5 the arm P^2 by means of the inclines B^8 and B^7 has raised the pawl O , as previously described, so as to allow the carriage I to slide to the right when acted on by the wedge B^4 . The drawer in closing engages 80 the arm N^3 of the rod N^2 , so that the latter is caused to slide rearward and by its pawls N' and N^6 turns the rollers J^6 and L^2 , whereby the tapes L and J are shifted, as above described. Part of the tape J is wound upon 85 the roll J^2 , while the front part or printed end of the tape L is pushed forward through the slot A^6 to be taken hold of by the operator and cut off by a spring-pressed knife Q , held on the front end A^7 of the casing. The coupon 90 thus cut off indicates a sale of one dollar and twenty-five cents. The recording-tape J always remains inside the locked casing A , so that no one except the authorized person has 95 access to the tape.

The tape L is divided into coupons with a blank space for the amount of the sale, each coupon bearing a suitable legend—such, for instance, as the words directly following the space for the amount of the sale "is the 100 amount of your purchase at the Central Drug Store," &c. It will be seen that by the shifting of the tapes L and J , as above described, new blank space is passed over the impression-block I' , so that at the next sale and operation, as above described, the amount of the second sale is printed on the said tapes.

It will be seen that by this device with only ten keys the operator is enabled to record any sale from one cent to ninety-nine dollars 110 and ninety-nine cents on a convenient paper tape easily removed from the machine, and which can be either copied or pasted in suitable books, thereby showing a perfect and convenient record of each day's transactions, 115 each cash or credit sale, by what salesman the sale is made, in which department, amount of cash paid out or received on account of goods returned, or change made, it being understood that the several parts last mentioned are engraved or printed by the extra type-bar H^5 , having a corresponding engraved plate H^6 . It will further be seen that a check or coupon is printed for each customer at each sale, so that the purchaser is enabled to compare the 120 value of his sale with the money paid. As the two tapes are printed on simultaneously and by the same type-bars, an error or discrepancy is impossible. It will further be seen that the machine is very simple and 125 durable in construction and not liable to get out of order.

Having thus fully described my invention, I claim as new and desire to secure by Letters Patent—

1. In a cash-recorder, the combination, with 5 a series of type-bars mounted to slide to and from a common center, of a paper-carriage mounted to slide transversely and carrying the paper and two tapes, a series of levers for shifting the said carriage in one direction, and a drawer mounted to slide and adapted to shift the carriage in the opposite direction, substantially as shown and described.

2. In a cash-recorder, the combination, with 15 a series of type-bars mounted to slide to and from a common center, of a paper-carriage mounted to slide transversely and carrying the paper and two tapes, a series of levers for shifting the said carriage in one direction and a drawer mounted to slide and adapted to shift the carriage in the opposite direction, substantially as shown and described.

20 3. In a cash-recorder, the combination, with a series of type-bars mounted to slide to and from a common center, of a paper-carriage mounted to slide transversely and carrying the paper and two tapes, a series of levers for shifting the said carriage in one direction and a drawer mounted to slide and adapted to shift the carriage in the opposite direction, and intermediate mechanism for connecting the said levers with the said carriage to shift the latter according to the 25 amount to be printed on the tapes, substantially as shown and described.

35 4. In a cash-recorder, the combination, with a series of type-bars mounted to slide to and from a common center, of a paper-carriage mounted to slide transversely and carrying the paper and two tapes, a series of levers for shifting the said carriage in one direction and a drawer mounted to slide and adapted to shift the carriage in the opposite direction, and a separate type-bar mounted to turn and carrying an inclined type-plate, substantially as shown and described.

40 5. In a cash-recorder, the combination, with a paper-carriage mounted to slide transversely, of a lever connected with the said carriage to shift the latter transversely when the said lever is pressed and a series of levers fulcrumed on the said first-named lever and each provided with a plate extending over the next following lever, so that when either of the levers of the series is pressed the said first-named lever is pressed and the carriage is shifted, substantially as shown and described.

45 6. In a cash-recorder, the combination, with a paper-carriage mounted to slide transversely, of a lever connected with the said carriage to shift the latter transversely when the said lever is pressed and a series of levers fulcrumed on the said first-named lever and

each provided with a plate extending over 55 the next following lever, so that when either of the levers of the series is pressed the said first-named lever is pressed and the carriage is shifted, and means, substantially as described, for limiting the downward movement 60 of the said series of levers to shift the carriage different distances, substantially as shown and described.

7. In a cash-recorder, the combination, with 65 a series of type-bars mounted to slide to and from a common point, of a paper-carriage mounted to slide transversely and carrying the paper and two tapes, a lever connected with the said carriage to shift the latter transversely, and a series of levers fulcrumed on 70 the said first-named lever and each provided with a plate extending over the next following lever, so that when either of the levers in the series is pressed the first-named lever is actuated and the carriage is shifted, substantially as shown and described.

75 8. In a cash-recorder, the combination, with a series of type-bars mounted to slide to and from a common point, of a paper-carriage mounted to slide transversely and carrying 80 the paper and two tapes, a lever connected with the said carriage to shift the latter transversely, and a series of levers fulcrumed on the said first-named lever and each provided with a plate extending over the next following lever, so that when either of the levers in the series is pressed the first-named lever is actuated and the carriage is shifted, and means to graduate and limit the downward 85 swinging motion of the levers to shift the carriage different distances, substantially as shown and described.

90 9. In a cash-recorder, the combination, with a drawer, of a locking-bolt adapted to engage a notch in the said drawer, a spring-pressed 95 lever pivotally connected with the said bolt to disengage the latter from the notch in the said drawer, and a series of levers pivoted on the said first-named lever and each provided with a plate extending over the next adjacent 100 lever to the left and over the said first-named lever, so that when either lever is pressed the said bolt is withdrawn, substantially as shown and described.
